UNITED STATES PATENT OFFICE

CHARLES W. SIMPSON, OF HARLINGEN, TEXAS

SUPPORTING HANGER FOR ROLLER SHADES

Application filed May 16, 1930. Serial No. 453,044.

The present invention relates to supporting hangers for roller shades and the primary object of the invention is to provide a device of this character adapted to support roller shades embodying plain rollers and not requiring the usual spring and ratchet arrangement for rolling up the shade.

A further object of the invention is to provide an improved hanger for roller shades which may either be mounted upon the face side of the architraves or between confronting surfaces of the window casing.

A further object resides in the novel construction of the hangers permitting ready use of the hangers at either end of the shade roller.

A still further object resides in the novel construction of the holder and the manner in which the same may be detachably associated with the mounting brackets to permit ready and easy mounting of the shade roller.

A still further and important object of the invention resides in the provision of improved hangers for shade rollers embodying adjustable tensioning means for frictionally engaging the ends of the roller whereby the shade may be retained in any desired position.

A further object of the invention resides in the provision of an improved roller shade hanger intended for rotatably supporting a shade roller having pull cords associated with the ends thereof for rotating the roller.

Other objects and advantages of the invention will be apparent during the course of the following detailed description, taken in connection with the accompanying drawings forming a part of this specification and in which drawings:

Figure 1 is a fragmentary face plan view of a window casing showing the hangers mounted upon the face of the casing.

Figure 2 is a perspective view of one of the adjustable holders for receiving one end of the shade roller.

Figure 3 is a perspective view of one of the mounting brackets.

Figures 4 and 5 are fragmentary sections on the respective lines in Figure 1.

Figure 6 is a fragmentary view showing the

hangers mounted at the inside of the window casing or between confronting surfaces thereof.

Figure 7 is a section on line 7—7 of Figure 6.

Figure 8 is a plan view looking at the rear side of one of the adjustable holders.

Figure 9 is a sectional view showing a slightly modified form of holder and an optional way of mounting the device as an outside hanger.

In the drawings, and wherein similar reference characters designate corresponding parts throughout the several views, the letter A may designate a window casing, B and C a pair of hangers for supporting a shade roller D of cylindrical formation and having wound thereon the shade E.

The casing A is of ordinary construction including the architraves 5 and the inside stop beads 6 having their exposed surfaces in parallel confronting relation. As in common practice, the ordinary types of spring wound roller shades may either be provided with "outside brackets" for mounting upon the face sides of the architraves or may be provided with "inside brackets" for mounting upon the confronting surfaces of the inside stop beads, the former ordinarily being called face or outside mounting and the latter inside mounting. The improved supporting hangers forming the subject matter of this invention are adapted for use either as outside or inside mountings for the roller shade.

The shade roller D is of plane cylindrical formation and is adapted to be rotatably supported at its ends in the hangers B and C.

Referring particularly to Figures 1 to 8 inclusive, the hangers B and C embody mounting brackets 8 and 10 respectively of reversible and like construction and each includes an adjustable holder 12 the holders being of identical construction for each of the hangers.

The mounting brackets 8 and 10 are of like construction and of angle shape providing a base plate 13 and a side plate 14. The brackets are preferably stamped from sheet metal doubled upon itself as clearly shown in Figure 3 with the portions of the base

plate slightly spaced apart to provide a passageway 15 opening at the upper and lower ends of the bracket. The spaced apart plates of the base 13 are provided with aligning end apertures 16 and intermediate apertures 17 while the end plate 14 is provided with apertures 18. The brackets 8 and 10 are provided with holder supporting frames 20 and 21 respectively which are removably associated with the base portions 13.

The supporting frame 20 is formed of wire and includes the yoke portion 22 adapted to be inserted upwardly thru the passageway 15 with the head piece 23 disposed above the top edge of the base portion and providing a transverse keyway 24 across the upper end of the base portion. The lower end of one arm of the yoke portion is bent inwardly toward the center of the base portion as at 25 and then forwardly at a right angle to the base portion and providing a rest portion 26. At the forward end of the rest portion 26 the wire is bent upwardly at an angle as at 27 and then in a direction away from the side plate 14 and formed into an elongated guide eye 28.

The supporting frame 21 is of substantially like construction as that of the supporting frame 20 and has the wire bent back upon itself as at 27' and continued rearwardly along one side of the rest portion and then bent at a right angle to the rest portion and formed into an elongated guide eye 28' as shown in Figure 5.

These eyes 28 and 28' serve as guides for pull cords 30 and 31 respectively wound in opposite directions upon the end portions of the shade roller D. The ends of the pull cords may be secured in any suitable manner to the shade roller and by observing Figure 1 it will be seen that the pull cord 30 acts to wind the shade E upon the roller D while the cord 31 will rotate the roller in an opposite direction for unwinding or lowering the shade. Since the cords 30 and 31 extend from opposite sides of the roller D it is required that the guide eyes be disposed at opposite sides of the roller for properly guiding the cords.

Referring now to the construction of the holders 12, the same comprise each a body portion preferably formed from a strip of spring material shaped to provide a vertical rear portion 32 provided at its lower end with a forwardly extending bottom portion 33 which is connected to the rear portion by a spacer loop 34. From the forward end of the bottom portion 33 is an upwardly and forwardly inclined portion 35 from the upper end of which is a rearwardly and upwardly inclined portion 36 upon the upper rear end of which is provided a head portion 37 formed by bending the metal upon itself as shown in Figure 2. Clamped at its upper end in the head portion 37 is a spring ten-

sioning arm or strip 38 having its lower arcuate end extending in spaced relation to the portions 35 and 36 and with its concaved side in confronting relation to the rear strip portion 32. The upper end of the portion 32 is formed in to a S hook 40 which is offset rearwardly from the portion 32.

Rotatably extended thru the head portion 37 and upper portion of the rear strip 32 is an adjusting screw 41 having threaded engagement in a nut 42 disposed at the rear side of the strip portion 32 and held against rotation by the hook 40. Threaded upon the screw 41 at the outer side of the head portion 37 is an adjusting nut 43 adapted for forcibly moving the head portion toward and away from the rear strip 32.

The compressible holders 12 are intended to be removably associated with the mounting brackets and may be positioned thereon by merely hooking the hooks 40 thru the transverse keyways 24 and then swung downwardly into a position resting upon the supporting frame rest portion with the inclined portions 27 or 27' engaging the inclined holder portions 35. The rest portion 26 will readily yield to permit the lower portion of the holder to move into position with the spacer loop 34 engaging the lower portion of the bracket base portion 13. When the holder is in position upon the bracket the inner end of the adjusting screw 41 is permitted to enter one of the sets of end apertures 16 as shown in Figure 4.

The ends of the roller D extend into the holders between the rear strip 32 and lower arcuate end of the spring arm 38 so that the arm 38 acts as a yieldable brake arm for preventing free rotation of the roller. The tension of the spring arms upon the ends of the roller may be varied by rotating the nut 43.

Referring particularly to Figures 1, 4 and 5 and wherein the hangers have been shown arranged for outside mounting of the roller shades, the brackets 8 and 10 are mounted upon the face side of the window casing by means of screws 45 passed thru the apertures 17 of the base plate 13. When the hangers are so mounted upon the face of the window casing the side plates 14 of the brackets serve to prevent longitudinal movement of the shade roller.

In Figures 6 and 7 the hangers are arranged for inside mounting of the roller shade and are secured to the confronting faces of the stop beads 6 by means of screws 46 passed thru the apertures 18 provided in the bracket side plate 14. Thus it will be seen that the brackets are adaptable for use as either inside or outside mounting hangers and that in each case the side plates 14 act to prevent longitudinal shifting of the shade roller.

By observing Figure 4 wherein the hanger

has been shown mounted upon the face of the casing it will be seen that only limited adjustment of the screw 41 could be had without the inner end of the screw contacting with the window casing and for this reason the adjusting nut 43 is provided for movement of the head portion 37 for placing the desired tension upon the spring arm 38.

Referring to Figure 9, a slightly different arrangement of mounting and constructing the holder has been disclosed and herein the adjusting screw 41, nut 42 and nut 43 have been dispensed with and a wood screw 50 passed thru the head portion 37', holder portion 32 and bracket base portion 13 and threaded into the window casing. In this arrangement, the screw 50 not only serves as an attaching means for the upper end of the hanger but also as a contracting means for the holder 12'. With this arrangement the holder is not removable from the bracket without removal of the combined attaching and adjusting screw 50. The arrangement shown in Figure 9 may only be used for outside mounting of the hangers as shown in Figure 1 and when inside mounting is desired as shown in Figure 6, the holder contracting means as shown in Figure 2 would be required inasmuch as the brackets are secured by means of the side plates 14. In the form of holder 12', the spring tensioning arm 38' is formed integral with the head portion of the holder, the holder being made from a strip of spring metal.

From the foregoing description it will be apparent that a novel and improved construction for supporting hangers for roller shades has been disclosed embodying a construction permitting of either inside or outside mounting of the roller shade. It will further be apparent that a novel arrangement has been shown whereby the shade roller may be easily and quickly mounted in the hangers. It will further be observed that a novel tensioning means for the shade roller has been provided whereby the desired friction upon the roller may be had for retaining the shade in any desired position.

Changes in the shape, size, and arrangement of parts may be made to the form of invention herein shown and described, without departing from the spirit of the invention or the scope of the following claims.

I claim:

1. A supporting hanger for shade rollers of the class described comprising a mounting bracket, and a contractible roller-receiving holder having an interlocking hooked connection at its upper end with the upper end of the bracket.

2. A supporting hanger for shade rollers of the class described comprising a mounting bracket having a keyway at its upper portion, and a contractible roller-receiving holder including a rear portion having hooked

engagement at its upper end in said keyway whereby the holder is pendently supported upon the bracket.

3. A supporting hanger for shade rollers of the class described comprising a mounting bracket having a slot formed across its upper portion, a yieldable rest portion at the lower end of the bracket, and a contractible roller-receiving holder having a hook at its upper portion for positioning in said slot and adapted to have its lower portion received in said yieldable rest portion.

4. A supporting hanger for shade rollers of the class described comprising an angle-shaped mounting bracket providing base and side plates, a supporting frame carried by the base plate and providing a transverse keyway at the upper end of the base plate, and a contractible roller-receiving holder including a back strip portion having a hook formed at its upper end for engaging in said keyway with the strip portion overlying the base plate.

5. A supporting hanger for shade rollers of the class described comprising a mounting bracket having a base portion, a supporting frame including a yoke portion carried by the base portion and including a head piece providing a keyway across the upper end of the base portion, and a contractible roller-receiving holder including a rear plate having a hook formed at its upper end for insertion thru said keyway into gripping engagement with the head piece of said yoke.

6. A supporting hanger for shade rollers of the class described comprising a mounting bracket including base and side plates, said plates each being provided with fastening element receiving apertures, a supporting frame carried by the base plate including a head piece extending in spaced relation above the upper end of the base plate and a rest portion extending forwardly from the lower end of the base plate, and a contractible roller-receiving holder including a rear portion having a hook formed at its upper end for engaging behind said head piece, a head portion, means for adjustably moving the head portion toward and away from the rear portion, and a spring tensioning arm carried by the head piece for frictionally engaging the circumference of a shade roller.

7. A supporting hanger for shade rollers of the class described comprising an angle-shaped mounting bracket having a transverse slot at its upper end, and a contractible roller-receiving holder for detachable connection with the bracket including a rear strip having a rearwardly offset hook at its upper end for hooked engagement in said slot, a forwardly extending bottom portion, and an upwardly and rearwardly bent front portion having a head provided at its upper end, a spring tensioning arm connected at its upper end to the head portion and having a curved

lower portion having its concaved side in confronting relation to the rear strip, and adjustable means connecting the head portion with the upper portion of the rear strip.

5 8. A supporting hanger for shade rollers of the class described comprising an angle-shaped mounting bracket including base and side plates, a frame including a head piece providing a transverse slot across the upper 10 end of the base plate and a rest portion extending forwardly from the lower end of the base plate, and a holder for removable positioning upon the bracket including a rear strip having a hook portion at its upper end 15 for hooked engagement with said head piece, a forwardly extending bottom strip, an upwardly extending portion with a head portion movable toward and away from the rear strip, an adjusting screw rotatably extending 20 thru the head portion and upper portion of the rear strip, a nut at the rear side of the rear strip into which said screw is threaded, an adjusting nut on the screw in bearing engagement with the outer side of the 25 head portion, and a yieldable tensioning arm carried by the head portion and yieldable toward and away from the rear strip.

9. A supporting hanger for shade rollers of the class described comprising an angle-shaped mounting bracket providing base and side portions, said portions each being apertured and said base portion being provided with a vertically extending way, a frame including a yoke portion disposed in said way, 35 a head portion extending in spaced relation above the upper end of the base portion, and a forwardly extending rest portion at the lower end of the base portion, and a holder including a rear portion having a hook provided at its upper end for engaging said head piece, a bottom portion extending forwardly from the rear portion and an upwardly extending portion at the forward end of the bottom portion and having a head portion 40 formed at the upper end thereof, said bottom portion having engagement upon said rest portion, a yieldable tensioning arm carried by the head portion and yieldable toward and away from said rear portion, and an adjustment screw connecting the head portion 45 with the upper end of the rear holder portion for movement of the head toward the rear portion.

10. In a supporting hanger for shade rollers of the class described, a mounting bracket of angle-shape providing base and side plates, said plates each being provided with fastening element receiving apertures, a supporting frame including a head piece spaced 55 above the upper end of the base plate, a contractible holder including a rear portion and a head portion, said rear and head portions having aligning apertures, a hook formed at the upper end of the rear portion for engaging the head piece of said base plate, a

yieldable roller engaging arm carried by said head portion, and an adjusting screw extending thru the aligning apertures in the head and rear portions of the holder and the upper aperture in the base plate of said bracket. 70

11. In a supporting hanger for shade rollers of the class described, a mounting bracket including base and side plates, said base plate having a keyway formed along its upper edge, a roller-receiving holder provided with a hook at the upper end of its rear portion for engaging in said keyway, and a spring tensioning arm, means for contracting the holder, and a rest for the lower end of the holder including an inclined arm portion normally urging the lower end of the holder toward said base plate. 75 80

12. In a supporting hanger for shade rollers of the class described, an angle-shaped mounting bracket providing base and end plates, a wire frame including a yoke portion carried by the base plate and having a head piece spaced above the upper end of the base plate, a rest portion extending forwardly from the lower end of the base plate and an elongated guide eye offset from the forward end of the rest portion, and a roller receiving holder having a hook formed at its upper side for hooked engagement with said head piece and adapted to have its lower portion resting upon said rest portion, means for contracting the holder, and a yieldable roller engaging arm carried by the holder for frictionally engaging the roller to various degrees thru adjustment of the contrasting means. 90 95 100
